UNITED STATES PATENT OFFICE.

JOHN F. MAHLSTEDT, OF LOS ANGELES, CALIFORNIA.

PRINTING-MACHINE.

1,160,185.

Specification of Letters Patent. Patented Nov. 16, 1915.

Application filed July 29, 1913. Serial No. 781,751.

To all whom it may concern:

Be it known that I, JOHN F. MAHLSTEDT, a citizen of the United States, residing at Los Angeles, in the county of Los Angeles and State of California, have invented new and useful Improvements in Printing-Machines, of which the following is a specification.

This invention relates to improvements in printing machines, and particularly to a machine of the nature shown in a previous patent of mine, No. 1,016,756, February 6, 1912, the present invention relating to the printing head and adjacent parts.

One of the objects is to construct the front stops as fingers, which project down from the top, and to actuate these fingers by a spring device operating in conjunction with the vertical movement of the feeding roller, which will compensate for irregularities.

Another object is to provide ejector rollers which are in plain view and accessible from the top. In my former patent the ejector rollers could not be seen and frequently the operator would mount a wider form of type and on account of not seeing the ejector roller would fail to adjust them wider apart to accommodate the wider form, and when the machine was operated the face of the type would rub under the old ejector, thus injuring the type. The improved construction enables them to be readily seen and adjusted to suit the width of the form. Other advantages will be brought out in the following description.

Referring to the drawings: Figure 1 is a side view of the printing machine with part broken away constructed in accordance with the invention. Fig. 2 is an enlarged plan view of the head in detail. Fig. 3 is a section on line x^3-x^3 , Fig. 4. Fig. 4 is a section on line x^6-x^4 , Fig. 2. Fig. 5 is a section on line x^5-x^5 , Fig. 2. Fig. 6 is a section on line x^6-x^6 , Fig. 4. Fig. 7 is a detail view of a plate to be hereinafter mentioned.

In a companion application of mine executed of even date herewith, and filed July 29th, 1913, Serial No. 781,750, I have shown and described other features of the printing machine, which may be used in connection with the head forming the present invention, and therefore the description in the present case will be confined to the features of the head, referring to the other features

only as it may be necessary to make clear the construction and operation of the head.

1 designates the frame of the machine with a traveling bed 2 carrying the form of type 3 and a ribbon 4 for printing from part of the form, and an inking roller 5 for directly inking other portions of the form.

6 designates ink tables which travel with the traveling bed 2, which act to supply ink to such rollers as may be employed for directly inking portions of the form which are not inked by the ribbon.

It will be understood that the details in connection with the features just mentioned form no part of the present invention, and are therefore not necessary to be shown. 70 The traveling bed is reciprocated by a lever 7 which is operated through a suitable gearing indicated in general at 8 and driven by a motor 9.

10 designates the printing head in general, 75 under which the traveling bed carries the form of type, and the sheets to be printed are fed from a table 11 toward the printing head 10, and after being printed are conveyed away from the printing head 10 by a 80 conveyer 12.

The printing head comprises an impression roller 13, which has two motions. It constantly revolves with a peripheral speed equal to the travel of the traveling bed, and 85 is intermittently raised and lowered with respect to the traveling bed, being lowered during the forward printing stroke to press the paper against the type and effect the printing, and being raised during the return 90 stroke of the traveling bed. The impression roller is mounted revolvably on a shaft 14 which is formed with eccentric ends 15 and 16, which are journaled in stationary bearings 17 supported on the frame 1. The eccentric ends 15 and 16 are in line with each other and rotatably mounted on the end 16 is a gear 18 having enlarged holes 19, which receive pins 20 projecting from the end of the impression roller 13, and meshing with 100 the gear 18 is a rack 21, which is rigidly secured to the traveling bed 2 and reciprocates therewith, thereby rotating the gear 18 in one direction during one stroke of the bed, and in the other direction during the 105 other stroke of the traveling bed. The large holes 19 permit the impression roller 13 to rotate on an axis eccentric to the axis

of rotation of the gear 18. Thus while the gear 18 always operates to revolve the impression roller with it, the impression roller is eccentrically adjustable to different elevations with respect to the traveling bed.

Mechanism is provided for automatically rotating the shaft 14 to intermittently move the impression roller 13 up and down, this mechanism consisting of a gear 22 rigidly secured on the eccentric end 15 and meshing with a rack 23, which does not travel with the traveling bed, but has a relatively short movement and is automatically shifted at the end of the stroke of the traveling bed as described in the companion application. The rack 23 has a projection 24 which when the rack is shifted rides under a roller 25 which is carried on a rock arm 26, which is rigidly secured to a shaft 27, and when the rock arm 26 is actuated it turns shaft 27. Rigidly mounted on shaft 27 are supporting arms 28, in which is journaled a feed roller shaft 29, upon which is mounted feed roller 30, which is adapted to contact with the sheet of paper when the feed roller is depressed and moves the paper into printing position. Rigid on the feed roller shaft 29 is a pinion 31, which meshes with an intermediate idle pinion 32, which in turn meshes with gear 18, so that the feed roller is constantly rotated first in one direction and then in the other corresponding to the reciprocations of the traveling bed.

In Fig. 5, 33 designates the paper which is fed by hand onto an inclined plate 34, which is recessed at 35 to receive a lower idle feed roller 36, and when the feed roller 30 is moved down it presses the paper 33 between the feed roller 30 and the feed roller 36 and moves the paper forward toward the compression roller. One end of the roller 36 is mounted in an eccentric bearing 36' shown in dotted lines in Fig. 5, which enables the roller 36 to be readily lined up parallel to the feed roller 30. The bearing 36' has attached to its outer end a slotted plate 36'', as clearly shown in Fig. 2.

The front stops against which the sheets of paper are manually fed comprise several spring fingers 37, which are carried on a hexagonal cross bar 38, this bar being pivoted in the side frame 39 and at one end carrying a bracket 40, which is actuated through the medium of a compression spring 41 moved upwardly by a lateral arm 42 from the rock arm 26 and bolt 43, passing through the lateral arm 42 and a lip 44 on the bracket 40 to hold the spring 41 in position. Whenever the rock arm 26 is moved upwardly the spring 41 yieldingly presses up on the bracket 40, and the latter moves down the spring fingers 37 so that their lower ends project into or slightly through the plate 34 as shown in Fig. 5, and thereby form positive front stops against which rests

the front edge of each sheet as it is fed into position by the operator. This upward movement of arm 26 takes place at the end of the forward stroke of the traveling bed, after which a fresh sheet is fed into position, so that after the conclusion of the stroke, the sheet is in position and ready to be shot forward by the feed roller when the latter descends at the commencement of the forward stroke of the traveling bed. As the feed roller thus descends the fingers 37 lift and release the sheet, allowing it to move forward. A screw 45 arranged on the bracket 40 is adapted to strike a stationary lug 46 and limit the upward swing of bracket 40. The rock arm 26 after having been moved up by the projection 24 of the sliding rack is restored by a compression spring 47, the tension of which is regulated by the screw 48 extending through lug 46.

In order to eject the sheet after printing, I provide ejector rollers 49 which are adjustable laterally so as to bear against the margin of the paper, each ejector roller being carried on a block 50, which is slidable laterally on a cross rod 51, and is located within a box 52, the latter being also slidable on cross rod 51, and further supported by another cross rod 53. Each box 52 is adjustable along the rods 51 and 53 and is detachably held in position by a thumb screw 54. In order to hold each ejector roller up in proper position, a spring 55 is provided which is coiled around the rod 51, one end of the spring bearing against a pin 56 on the block 50, and the other end bearing on the under side of the box 52. A pair of guide fingers 57 extend under the impression roller 13, the respective fingers extending along the top of the respective boxes 52, and being secured thereto by binding its end over as at 58. The other end of each guide finger is formed with a hook 59 to engage a flange 60 formed on the lower edge of the plate 34. This construction supports the ends of the fingers 57, and yet permits them to be slidably adjusted laterally of the machine by loosening the thumb screws 54. The guide fingers are easily accessible from the top of the machine, and in full view. They may readily be adjusted laterally of the machine to suit the size of the form so that they will not interfere therewith.

What I claim is:

1. In a printing machine, printing means, a plate for guiding the paper toward the printing means, front stops comprising fingers above said plate, the lower ends of which fingers are adapted to be projected downward into said plate to arrest the forward edges of the paper, a feed roller bodily movable into contact with the paper to feed the paper toward said front stops, a shaft independent of said feed roller carrying

said fingers, a bracket on said shaft, a rock arm, a compression spring between said rock arm and said bracket, and means coöperating with the printing means for tilting said 5 rock arm to actuate the front stops independently of the feed roller.

2. In a printing machine, printing means, a plate for guiding the paper toward the printing means, front stops comprising fingers, the lower ends of which are adapted 10 to project into said plate and arrest the forward edges of the paper, a shaft carrying said fingers, a bracket on said shaft, a rock arm, a compression spring between said 15 rock arm and said bracket, and means coöperating with the printing means for tilting said rock arm, a feed roll, arms supporting the same, a shaft supporting said arms, said rock arm being attached to said 20 last mentioned shaft.

3. In a printing machine, printing means, a plate for guiding the paper toward the printing means, front stops comprising fingers, the lower ends of which are adapted 25 to project into said plate and arrest the forward edges of the paper, a shaft carrying said fingers, a bracket on said shaft, a rock arm, a compression spring between said rock arm and said bracket, and means

coöperating with the printing means for 30 tilting said rock arm, a feed roll, arms supporting the same, a shaft supporting said arms, and means securing the rock arm to said last mentioned shaft and for varying the angular relation of the rock arm to the 35 shaft.

4. In a printing machine, the combination of upper and lower feed plates, upper and lower feed rolls, a bail shaft, means for supporting the upper feed roll from said 40 shaft, a post secured to said shaft, means acting on said post for raising the same when not printing and lowering the same when printing, a lateral extension to said post, a stop finger shaft, a pacifier bracket 45 carried by said stop finger shaft over said lateral extension and having a sliding connection therewith, and fingers depending from the stop finger shaft and having their ends adapted to pass through openings in 50 the lower feed plate when the post is raised.

In testimony whereof, I have hereunto set my hand at Los Angeles, California, this 16th day of July, 1913.

JOHN F. MAHLSTEDT.
